COIN-CONTROLLED AMUSEMENT GAME
APPARATUS

Eldon L. Dale, Long Beach, Calif.

Application October 16, 1952, Serial No. 21,861

Term of patent 14 years

(Cl. D34—5)

To all whom it may concern:

Be it known that I, Eldon L. Dale, a citizen of the United States, and a resident of Long Beach, in the county of Los Angeles and State of California, have invented a new, original, and ornamental Design for a Coin-Controlled Amusement Game Apparatus, of which the following is a specification, reference being had to the accompanying drawing forming a part thereof, and in which:

Fig. 1 is a perspective view of a coin-controlled amusement game apparatus showing my new design;

Fig. 2 is a fragmentary side elevational view thereof, the control wheel and chute being omitted for convenience of illustration; and

Fig. 3 is a top plan view of the playing field embodied in my design, to a reduced scale.

I claim:

The ornamental design for a coin-controlled amusement game apparatus, as shown and described.

ELDON L. DALE.
